UNITED STATES PATENT OFFICE.

JAMES H. SAGER, OF ROCHESTER, NEW YORK.

DESIGN FOR AN AUTOMOBILE-BUMPER.

42,149.

Specification for Design.

Patented Feb. 6, 1912.

Application filed October 21, 1911. Serial No. 656,013. Term of patent 7 years.

To all whom it may concern:

Be it known that I, JAMES H. SAGER, a citizen of the United States, residing at Rochester, in the county of Monroe and State of New York, have invented a new, original, and ornamental Design for an Automobile-Bumper, of which the following is a specification, reference being had to the accompanying drawing, forming part thereof.

The drawing is a perspective view of an automobile bumper showing the novel design hereinbefore referred to.

I claim:

The ornamental design for an automobile bumper, as shown.

JAMES H. SAGER.
